United States Patent Office.

JAMES McINTIRE, OF HOPEWELL COTTON-WORKS, PENNSYLVANIA,
ASSIGNOR TO W. C. DICKEY

Letters Patent No. 99,099, dated January 25, 1870; antedated January 14, 1870.

IMPROVEMENT IN CORD-MAKING MACHINE.

The Schedule referred to in these Letters Patent and making part of the same.

To all whom it may concern:

Be it known that I, JAMES McINTIRE, of Hopewell Cotton-Works, in the county of Chester, and State of Pennsylvania, have invented a new and improved Twister for Twine; and I do hereby declare that the following is a full, clear, and exact description of the construction and operation of the same, reference being had to the accompanying drawings, making a part of this specification, in which—

Figure 1 is a side view.

Figure 2 is a horizontal section, through line $z z$ of fig. 1.

This invention relates to the device patented by J. Mcintire, June 22, 1869; and consists in a simple and convenient substitute for the standards and leather belt around the lower ends of said spindles.

In the drawings—

B B B represent the bobbins;

b b b, their spindles;

c c c, the wheels or circular disks near the lower end of the spindles, and which, by friction against the surrounding belt, impart a rapid rotary motion to the bobbins;

a a, the thread-guides;

t t, the threads;

D, the central spindle or shaft;

E, the belt-pulley, by which it is operated;

F, the plate which supports the bobbin-spindles, itself being supported upon a plate, G, to which it is connected by standards g g; and

I I, the jointed arms which support the upper ends of the bobbin-spindles.

All these parts are similar in construction and operation to corresponding parts in the apparatus patented June 22, 1869, above referred to, and constitute no part of my present invention, which consists in certain improvements to be used in connection with these parts, which I will now more particularly describe.

In practical operation, it is found that unless the arms I I are held down, they will occasionally work up while the machine is running, and become disengaged from the bobbin-spindles, throwing the whole apparatus out of working-order. To remedy this, a collar, m, is provided, having four or more arms, n n, which slips down upon the shaft D, until it rests on the fixed collar, to which the arms I I are pivoted, in which position its arms n n extend beyond the joints i, and rest upon the upper side of the arms I I, coinciding exactly in number and position with said arms. This collar is fixed to the shaft D, by means of a set-screw, s, as shown in the drawings, when it holds the arms I I securely down upon the bobbin-spindles, and prevents all inconvenience arising from the cause above referred to.

Instead of the leather belt, secured by standards, as described and shown in my former patent, I now employ an annular plate or ring, composed of several independent curved segments, r r, each segment supported by two (more or less) spring-standards, u u.

The standards are each provided with a slotted foot or base-flange, o, upon which they rest on plate G, and with a set-screw, v, operating in the slot, by means of which they can severally be adjusted in or out on said plate, so as to increase or decrease the friction between the ring r r and the disks c c, and thus perfectly regulate the action of said parts.

This device is found to be more simple, convenient, and effective in practical operation than anything, for a similar purpose, heretofore brought into use.

Having thus described my invention,

What I claim as new, and desire to secure by Letters Patent, is—

The curved segments r r, when supported upon flexible elastic standards u u, and provided with an adjusting-apparatus, o v, and arranged in connection with the disks c c c, substantially as and for the purposes specified.

JAMES McINTIRE.
